Primary Examiner — Melanie Pellegrini(57) **CLAIM**

The ornamental design for a finger ring, as shown and described.

DESCRIPTION

1. Finger ring
2. Finger ring
- 1.1 : Exploded
- 1.2 : Perspective
- 1.3 : Front
- 1.4 : Back
- 1.5 : Top
- 1.6 : Right
- 2.1 : Exploded
- 2.2 : Perspective
- 2.3 : Front
- 2.4 : Back
- 2.5 : Top
- 2.6 : Right

The solid lines of the design illustrations show the parts of the product that claim protection; the dash-dotted lines indicate the transition from the protected part to the non-protected part of the designs; each design shows a size adjustment system for finger rings.
